St. Clair Shores, Mich., assignors to Chrysler Corporation, Highland Park, Mich., a corporation of Delaware

Application July 26, 1955, Serial No. 37,126

Term of patent 14 years

(Cl. D14—18)

Fig. 1 is a side elevational view of an ornament for an automobile hood, showing our novel design;

Fig. 2 is a top plan view thereof;

Fig. 3 is a front elevation of the ornament; and

Figs. 4, 5, 6, 7, 8, 9, 10, 11 and 12 are sectional views taken on the lines 4—4, 5—5, 6—6, 7—7, 8—8, 9—9, 10—10, 11—11 and 12—12, respectively, of Fig. 1.

We claim:

The ornamental design for an ornament for an automobile hood, substantially as shown.
